UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

YARN SUPPORT AND GUIDE FOR WINDING-MACHINES.

1,307,700.

Specification of Letters Patent. Patented June 24, 1919.

Application filed October 5, 1918. Serial No. 256,946.

To all whom it may concern:

Be it known that I, ALONZO E. RHOADES, a citizen of the United States, and resident of Hopedale, county of Worcester, State of Massachusetts, have invented an Improvement in Yarn Supports and Guides for Winding-Machines, of which the following description, in connection with the accompanying drawing, is a specification, like characters on the drawing representing like parts.

This invention relates to improvements in yarn supports and guides for winding machines in which the yarn supplying means are so wound as to require the running strand to be drawn off substantially in the axis of the yarn supplying means as in the case of "filling wound" bobbins.

In order to unwind such yarn supplying means it is desirable to provide guiding means positioned closely to the nose of, and substantially in line with the axis of the bobbins. In usual yarn winding machines such as spooling machines the yarn supplying means are supported upon relatively short studs which enable the yarn supplying means to be doffed and replaced beneath the guiding means.

As bobbins vary in size, shape and length and have bores of different diameters it is in many instances impossible to retain them upon the short studs of the usual spoolers. If longer spindles are employed, which will properly support bobbins of different sizes and having different bores the guiding means for the running strand has to be located so far from the nose of the bobbin, to provide for doffing and replacement, that the running strand is not properly drawn off of the bobbin.

The principal object of the present invention is to provide a combined support for the yarn supporting means or bobbin and a guiding means for the running strand in which a relatively long spindle adapted to support any kind of bobbin or yarn supplying means may be employed and a guiding means positioned closely adjacent the nose of the bobbin.

This is accomplished in the present invention by providing a bracket having a

relatively long spindle and securing to the upper end of the bracket a guide, which when in normal position is in the axial line of the spindle, but which may be removed, preferably by being swung aside, to permit the doffing and replacement of the bobbins or other yarn supplying means.

A further object of the invention is to provide a guiding means of the character specified which when swung aside to permit the placing on or the taking off of the bobbins will automatically return to its normal guiding position when released by the operator.

A further object of the invention is to provide a bobbin guide of the character described which will be returned to its guiding position by the force of gravity thereby avoiding the necessity of springs.

Other objects of the invention will more fully appear from the accompanying drawing and will be pointed out in the annexed claims.

In the drawings;

Figure 1 is a vertical sectional view of a sufficient portion of a usual spooling machine to illustrate my invention as applied thereto,

Fig. 2 is a side view of a bobbin supporting bracket and yarn guide embodying my invention,

Fig. 3 is an enlarged plan view of the same showing in full lines the guide in normal position and in dotted lines the guide swung aside to permit doffing of the bobbin, and,

Fig. 4 is a detail end view of the guide for the yarn showing the manner in which it is pivotally supported upon the bracket.

The spooler which is illustrated in the accompanying drawings is of a usual type comprising a frame 1 having the usual top rail 2 upon which is mounted a series of spindles 3 which are adapted to be rotated by whirls 4, said spindles being provided with means for supporting spools or other yarn receivers 5. The yarn receivers 5 are rotated in the usual manner by belts passing around a driving drum 6 and the whirls 4. The yarn is caused to traverse the spools 5 by guides 7 secured to a traverse rod 8 which

is carried upon rocker arms 9 extending upwardly from shaft 10 which are oscillated through yokes 11 in the customary manner.

- 5 The construction thus described is of a usual character and my invention contemplates an improved support for the bobbins and guide for directing the running strand as it leaves the bobbin to be drawn through 10 the guide upon the traverse rod to the spool.

A preferred bobbin support which is illustrated herein comprises a bracket 12 having means, such as a notch 13 and opposing set screw 14, for securing the same to 15 a rod 15 extending longitudinally of the spooler frame and supported therefrom by brackets 16.

The bracket 12 has at its lower end a lateral extension 17 which supports a spindle 18 which may be provided with conical sections 19, 20 and 21 of different diameters.

The bracket is also provided with an arm 22 extending upwardly to a distance somewhat beyond the end of the spindle 18. The upper end of the arm 22 has a laterally extending boss 23 which is bored longitudinally to receive the pivotal stud 24 of the yarn guiding means. The yarn guiding means comprises a member 25 which preferably extends upwardly and laterally from the bracket arm 22 and has a bifurcated extension 26 which forms a V-shaped guide for the running strand, the apex of 25 the bifurcation preferably being in alignment with the axis of the spindle 18 when the guide is in normal position as illustrated in full lines in Fig. 3. The upper end of the bracket arm 22, or the boss 23, 30 is provided with an upward extension 27 extending partially around the pivotal stud 24, the face of said extension presenting a shoulder 28 adapted to engage a complementary shoulder upon a downward extension 29 on the guiding member 25. The shoulder 28 is so positioned that when the downward extension 29 of the guiding member 25 engages it, the apex of the thread guiding recess in the bifurcated extension 26 will be positioned directly over the axis of the spindle. It will thus be obvious that when in normal position the guide may be located in such proximity to the bobbin as to direct the yarn running from the bobbin substantially in the axial line of the bobbin and that it may be swung aside to enable the bobbin to be placed upon or removed from the spindle.

When placed upon the spooling frame, 60 the bracket desirably is secured in a position inclined to the horizontal approximately 45 degrees and the connection between the bracket and guiding means is such that when in this position the guiding means will return by gravity to its nor-

mal position in line with the axis of the bobbin. Thus the necessity for springs or locking means for securing the guide in place is avoided and a simple construction provided which will not be likely to become 70 broken.

When the empty bobbins are to be replaced by fresh ones, it is merely necessary to swing aside the pivotally mounted guide to enable the empty bobbin to be pulled 75 directly off of the spindle and a new bobbin to be placed upon the spindle. When the guide is released it will instantly return to normal position by gravity whereupon the yarn may be carried directly up 80 to the traverse mechanism and led to the spool without the necessity of threading its end through an eye, so that a considerable amount of the operator's time is saved in replenishment.

It is to be understood that the specific embodiment of the invention disclosed herein is of an illustrative character and that various modifications in form and construction may be made within the meaning and 85 scope of the following claims.

Having thus described my invention, what I claim as new and desire to secure by Letters Patent is:

1. In a spooler, a support for bobbins 95 having a filling wind comprising a stand having a spindle for the bobbin and a guide pivotally mounted on said stand normally positioned to direct the running strand substantially axially of said bobbin but capable of being swung from said position to permit the doffing of the bobbin, said guide tending under the action of gravity to return to normal position.

2. In a spooler, a bobbin support comprising a bracket having a spindle positioned at an inclination to the horizontal, an arm extending in parallelism with said spindle, a guide pivotally mounted upon the upper end of said arm, means for limiting the pivotal movement of the guide under the action of gravity to hold the guide in position to direct the strand running from the bobbin substantially axially of the bobbin but capable of being swung aside 100 to permit the doffing of the bobbin.

3. In a spooler, a bobbin support comprising a bracket having a spindle positioned at an inclination to the horizontal, an arm extending in parallelism with said 105 spindle, a guide overhanging the end of the spindle pivotally mounted upon the upper end of said arm and said guide and said arm having coöperating shoulders to limit the movement of said guide, so positioned that the guide will normally be held by gravity in position to direct said strand axially of said bobbin but enabling the guide to be swung aside to permit the doffing 110 of the bobbin.

4. A bobbin stand for spoolers comprising a bracket having means for adjustably attaching the same to the side rail of the spooler at any desired inclination, a spindle for the bobbin, an arm extending in parallelism with said spindle, a guide pivotally mounted thereon overhanging the end

of the spindle and acting to direct the running strand of yarn substantially axially of said bobbin and means to limit the extent of swinging movement of said guide.

In testimony whereof, I have signed my name to this specification.

ALONZO E. RHOADES.
